PAPER TACKING MACHINE

Fritz Rau, Munich, Germany, assignor of one-third to Mrs. Heinrich Bruns and one-third to Heinrich Steinberg, both of Munich, Germany

Application January 18, 1932, Serial No. 587,383,
and in Germany February 28, 1931

1 Claim. (Cl. 93—1)

The present invention relates to a paper tacking machine, wherein the paper, that is to be clipped or tacked together is passed through between two wheels provided with wedge shaped 5 teeth thus tacking the paper sheets together. Such machines are already known per se. The essential feature of the present invention as hereinafter described lies in the resilient mounting of one of the tacking members.

10 The invention is described hereinafter. The drawing shows a section through the machine.

In the case of such tacking machines as hitherto known, one of the tacking elements was mounted either in or on a yielding or resilient lever, or 15 in cross pieces provided with rubber buffers or in guiding slides. All these designs however have the disadvantage that the resiliency i. e. the ability to yield of one of the tacking members does not act quickly enough, as this type of resilient mounting has in the first instance to overcome certain frictional resistances, a fact which is very deleterious considering that the various documents to be tacked together are frequently made of paper of varying thickness.

20 I have designed a mounting which ensures a substantially frictionless yet resilient action and which is also very cheap to manufacture. I have ascertained by experiments that the present invention enables a very much larger number of 25 sheets of paper to be securely tacked together than was hitherto possible, a fact which is solely due to the elasticity of the mounting of one of the tacking members.

The tacking or crimping machine which essentially comprises a body 3 is clamped on the table 1 by means of the clamping screw 2.

The bottom tacking or crimping wheel 4 is mounted in the body 3 and can be rotated by means of a crank handle 5. The top tacking or 40 crimping member or wheel 6 is mounted and loosely rotates on a slightly bowed spindle 7 consisting of resilient steel wire. This resilient steel wire spindle is at one end mounted in a bearing journal or sleeve 9 which is pressed into a suitable bore

in the body 3, and is at its other extremity mounted in the bore provided in a regulating screw 8. This regulating screw 8 can be axially displaced thus causing the spindle 7 to be more or less bowed and the tacking wheel 6 to be pressed more or less 50 against the bottom tacking wheel or member; Rotation of the regulating screw in a clockwise direction increases the pressure between the two tacking or crimping wheels. A table 10 is provided which serves to carry the paper to be crimped together. The device above described is an embodiment of the invention; it is of course self evident that it would also be possible to make the spindle of a bundle of resilient steel wires instead of only 55 of one such wire. The machine functions as follows, viz:

The paper to be tacked or crimped together is passed through two wheels 4 and 6, provided with teeth of a special shape the paper being rolled through between said wheels by rotating them by 75 means of the crank handle 5, it being possible for the top tacking wheel 6 which is mounted directly on a resilient spindle to adjust itself instantly to the various thicknesses of the papers to be tacked together without having first of all to 60 overcome frictional resistances. The extent of the pressure exerted may be adjusted according to the thickness of the papers by means of the adjusting screw 8.

I claim:

85 A paper tacking or crimping machine comprising a pair of interengaged crimping wheels, a shaft to rotate one of said wheels, a fixed bearing for said shaft, a resilient, bowed shaft for the other wheel on the bowed portion of which the 90 said wheel is mounted loosely for rotation, and means to support the ends of said resilient, bowed shaft, said supporting means including adjustable means for axially moving one end of said shaft to thereby vary the extent of the flexure thereof 95 and hence correspondingly vary the pressure between the two crimping wheels.

FRITZ RAU.
